MULTIPLE BLOCK MOLD

Martin M. Case, Roanoke Rapids, N. C.

Application August 6, 1946, Serial No. 688,756

1 Claim. (Cl. 25—121)

1

This invention relates to multiple block molds and more particularly to improvements in molds for making corner blocks, half blocks, and full blocks.

It is an object of this invention to provide an improved mold as forms for use in the manufacture of concrete building units.

It is another object of this invention to provide block molds from standard parts which may be easily assembled to produce forms for corner blocks, half blocks, regular blocks, or other desired irregular or partial blocks from poured concrete.

It is an object of this invention to provide an improved block mold assembled from sheet metal sections which may be readily removed from the blocks molded therein for reassembly and reuse.

It is an object of this invention to provide block mold parts which may be assembled quickly in various combinations to provide sturdy molds for various forms of poured concrete blocks.

It is a further object of this invention to provide improved block molds of the general type disclosed in U. S. Patent No. 1,282,607, issued to John F. McElroy et al., October 22, 1918.

Other objects and advantages of the invention will be readily apparent from the following detailed description of embodiments of the invention shown in the accompanying drawing wherein:

Figure 1 is a plan view of a multiple mold for use in making corner blocks.

Figure 2 is an expanded sectional view taken on line 2—2 of Figure 1.

Figure 3 is a perspective view of a corner block formed in the mold of Figure 1.

Figure 4 is a vertical section view of the preferred form of partition used in multiple molds of Figures 1, 2, and 6 to separate one block from another.

Figure 5 is a perspective view of one element of the partition member used in the corner block mold of Figure 1.

Figure 6 is a perspective view of a multiple mold for use in making regular blocks and/or half blocks.

Figure 7 is a plan view of a portion of the mold of Figure 6 illustrating the use of a removable partition for making half blocks.

Figure 8 is an elevational section view taken on line 8—8 of Figure 7.

Referring now to the drawings for the purpose of illustration, the multiple mold for corner

2

blocks shown in Figure 1 includes parallel side members 10 and 11 connected by five partition members 12. The side member 10 preferably has a channel cross-section as shown in Figure 2, including a projecting channel 13 to form an end groove in the corner block 14, one of the latter being illustrated in Figure 3, removed from the mold. Each of the partition members 12 has a projecting channel portion 15 on each side face thereof to form the side grooves in the block 14. The side member 11 has an outwardly projecting channel 16 extending along the length thereof and is provided on its inner face with a plate 17 having spaced slots 18 therealong. The end of each partition member 12 adjacent the plate 17 has a projecting tab 19 to extend through the slot 18 into the channel 16. Referring particularly to Figure 4, the partition members 12 may be formed from sheet metal of about 22-gauge thickness and preferably includes a central flat plate 20 between two channelled members 21 and 22, the three parts being riveted together. The lower longitudinal edges of the members 21 and 22 are flanged outwardly and clamped together by a C-shaped clip 23. The upper edge 24 of member 22 is turned over the upper edge of member 21 to provide added strength. The use of the central plate 20, the clip 23, and the turned over edge 24 provide a durable and strong partition member which may be reused many times. The side members 10 and 11 are assembled and may be held rigidly to one another with the partition members 12 extending therebetween by means of clamping straps 25 engaging angle iron brackets 26 fitted against the outer ends of the side members 10 and 11, one end of each strap being provided with an eccentrically mounted clamping handle 27. The side member 10 may be provided with inturned lugs 28 to engage the inner surface of the projecting channels 15 of the partition members 12 to properly space the partition members along the side member 10. The corner block mold shown in Figure 1 includes five partition members 12 for making four corner blocks 14 at one side.

Referring now to the multiple mold illustrated in Figure 6, the mold includes side members 30 and 31, similar to side member 10 of the Figure 1 construction, and partition members 32, similar in cross-section to the partition member illustrated in Figure 4. The side members 30 and 31 have inwardly directed channels 33 and 34 to form grooves in each end of the blocks molded therein. The projecting

channel portions 15 of the partitions 32 may be provided with vertical slots cut therethrough at or near the center to receive and position rectangular plates 35 when it is desired to mold half blocks. The end partition members 32 may be formed with a flat outer face, or may be similar to the partitions 32 with a projecting channel on each face, as shown. The multiple block mold of Figure 6 may be held in the assembled position shown by means of straps 25 extending through some of the hollow partition members 32 from side member 30 to side member 31, angle iron members 36 being provided on the outer faces of the side members, and the straps 25 being provided with eccentrically mounted clamping handles 37, similar to those shown in the Figure 1 construction.

The use of the multiple mold described above will be readily apparent to those skilled in the art. For making corner blocks, the mold is assembled as shown in Figure 1 and supported on a flat horizontal surface or pallet. A cement or concrete mixture of fluent consistency is poured into the mold and may be tamped, rolled or vibrated to insure that it fills all spaces between the side members and the partition members. As soon as the mixture has set or hardened sufficiently, the clamping straps 25 are removed and the mold disassembled. The mold parts removed from the molded blocks may then be reassembled for molding additional blocks. In the mold illustrated in Figures 6, 7, and 8, the mold is assembled and plates 35 are positioned in vertical slots in the channels 15 of the partitions 32 when it is desired to mold half blocks. The mold shown in Figure 6 is assembled for molding six half blocks and eight complete blocks. Obviously the molds may be constructed to form any number of complete or modified blocks. The molds are easily removed from the

molded blocks and the mold parts may be reassembled and reused many times. The sturdy construction of the partition members 12 and 32 provides for a long life mold. Although the constructions illustrated are believed preferable, it will be understood that numerous changes may be made within the scope of the invention defined in the following claim.

I claim:

In a mold for forming blocks, a transverse partition member comprising in combination three pieces of sheet metal secured together, and a transverse C-shaped clip reinforcing the lower transverse edge of said partition member, the outer two sheets of said partition member each having an outwardly projecting transverse flange along its lower edge, the upper transverse edge of one of said outer sheets being folded over and enclosing the upper transverse edge of the other outer sheet, said transverse clip engaging the said lower edge flanges of the said outer two sheets, said third piece of sheet metal being flat and secured between the said outer two sheets, and being of less width than the distance between said lower flange-engaging clip and said folded over upper edge.

MARTIN M. CASE.
